(57) **CLAIM**

The ornamental design for a shoe upper, as shown and described.

DESCRIPTION

FIG. 1 is a perspective view of a shoe upper in accordance with my new design.

FIG. 2 is a top plan view thereof.

FIG. 3 is a right elevational view thereof.

FIG. 4 is a left elevational view thereof.

FIG. 5 is a front elevational view thereof; and,

FIG. 6 is a rear elevational view thereof.

Broken lines in the figures are for illustrative purposes only and form no part of the claimed design.
